DIAPHRAGM PUMP

Clarence L. Pritchard, San Leandro, Calif., assignor to Malsbary Manufacturing Company, Oakland, Calif., a corporation of California

Application May 12, 1955, Serial No. 507,880

4 Claims. (Cl. 103—150)

The present invention relates to improvements in a diaphragm pump, and its principal object is to provide a heavy rubber bumper for cushioning the drive strokes of the diaphragm and for effecting the return stroke.

It is a further object of the invention to substitute the heavy rubber bumper for the spring previously employed for this purpose, since it has been found that the rubber bumper offers certain advantages over the spring in smoothness of operation, durability and effectiveness.

It is a further object of my invention to provide means for mounting the rubber bumper with respect to the diaphragm whereby the bumper may be readily clamped upon the diaphragm in a single movement and may as easily be removed for replacement purposes.

It is additionally proposed to provide means for securing the rubber bumper to the diaphragm in such a manner that it becomes part of the latter, and that the diaphragm and the bumper become a single unit for ease in assembling operations.

And finally, it is proposed to provide a fixed seat on the pump chamber for the bumper to bear against, the seat being formed with an annular flange for confining the free end of the bumper.

Further objects and advantages of my invention will appear as the specification proceeds, and the new and useful features of the same will be fully defined in the claims attached hereto.

The preferred form of my invention is illustrated in the accompanying drawing, forming part of this application, in which:

Figure 1 shows an axial section through a diaphragm pump having my rubber bumper incorporated therein;

Figure 2, a vertical central section through the bumper; and

Figure 3, a plan view of the bumper.

While I have shown only the preferred form of my invention, it should be understood that various changes or modifications may be made within the scope of the claims attached hereto, without departing from the spirit of the invention.

Referring to the drawing in detail, my diaphragm pump 1 may be of any suitable or preferred construction, and is here shown as comprising a housing 2 including a lower section 3, an upper section 4, and a diaphragm 5 of conventional construction clamped between the two sections by means of bolts 6 extending through registering flanges 7.

The diaphragm may have an outer ring 8 encircling the same.

The upper section of the housing forms the pump chamber and has an inlet port 9, controlled by a suitable intake valve (not shown) and an outlet port 10, controlled by the discharge valve 11, which is normally forced upon the valve seat 12 by means of a spring 13.

The valve seat is formed by the upper edge of a sleeve 14 fixedly mounted in a reduced waist section 15 of the housing. This sleeve ends below the waist section, and terminates in a closed bottom 16 formed with an annular

2

flange 17 to provide an annular pocket in opposing and spaced relation to the central section of the diaphragm.

The sleeve 14 is formed, below the waist, with a series of openings allowing liquid to pass therethrough into the sleeve for final discharge through the outlet 10.

The inner portion of the diaphragm, which is made of flexible material, preferably rubber reinforced by fiber, is made to flex back and forth in a reciprocating movement in the operation of the pump. It is provided with a drive plate 18 having a flat bottom face 19 and an upper face which is flat in its central section 20 and tapered in its outer section 21.

A washer plate 22, co-extensive in diameter with the flat section 20, is mounted on top of the central portion of the diaphragm.

The two plates 18 and 22 are held in assembled relation with respect to the diaphragm by means of an axial bolt 23, which has a head 24 bearing against the bottom face of the driving plate 18, extends through the assembly and has a nut 25 threaded upon its upper end and bearing upon the washer plate 22.

The extreme end of the bolt shank projects slightly above the nut, when the latter is screwed home, as at 26.

Between the upper washer plate 22 and the bottom face of the sleeve 14, there is mounted a heavy block 27 of compressible rubber, which, in its free state is preferably conical in form, as shown in Figure 2, and which has a lower diameter equal to that of the washer 22 and an upper diameter corresponding to the inner diameter of the flange 17.

When the diaphragm is at the end of the suction stroke, the rubber body 27, which is hereinafter referred to as the bumper, extends from the washer 22 into the pocket defined by the flange 17 while retaining its conical form, but still preferably under slight compression.

During the compression stroke of the diaphragm, the bumper expands sidewise to bulge out as shown in Figure 1 and to build up pressure for the return or suction stroke.

The bumper is secured upon the diaphragm assembly to form a unit therewith by shaping the bottom of the bumper with a recess 28 having a tight, clamping fit with the nut 25 and a reduced extension recess 29 fitting tightly on the extremity 26 of the bolt shank.

Thus, the bumper may be readily applied by pressing the recessed bottom upon the nut and the end of the bolt.

The drive for the power stroke is conventional and comprises a shaft 30 mounted transversely in the lower housing section 3, in bearings 31 and having a central eccentric section 32 between the bearings.

A tire 33 is mounted on the eccentric section, through a bearing 34 and contacts the bottom face of the bolt head 24, the various parts being located and dimensioned so that on the power stroke, the eccentric flexes the diaphragm upward as shown in Figure 1, while on the suction stroke it allows the bumper to flex the diaphragm downward.

The shaft may be revolved by any suitable means, as by the pulley 35.

In operation:

As the eccentric rotates through a one-half revolution from the position shown in Figure 1, it frees the diaphragm for downward movement, and the bumper, exerting downward pressure on the diaphragm, flexes the latter downward while the bolt head remains in contact with the eccentric tire.

During this stroke, the discharge valve 11 closes, and the intake valve opens, causing liquid to enter into the pump chamber through the port 9.

During the second half of the revolution of the crank shaft, the eccentric causes the diaphragm to flex upward

and to compress the bumper into the form shown in Figure 1. The diaphragm forces the liquid present in the pump chamber through the outlet valve 11, while closing the intake valve for port 9.

Thus the bumper serves to cushion the drive stroke, to effect the suction stroke and to insure a smooth transition from one stroke to the other.

The bumper may be easily applied in a single movement by merely pressing it upon its seat and it becomes then a part of the diaphragm assembly. It may also be easily removed for replacement purposes and is wear-resistant under the conditions prevailing in a pump chamber to a much greater degree than any metallic spring used for the same purpose.

In pumps of the character described, it is customary to provide a metering valve in the intake so as to allow the volume of discharge to be controlled. This makes it desirable to limit the suction stroke to the exact amount of water available for filling the pump chamber in order to prevent the creation of a vacuum which would cause a portion of the water to be vaporized.

In order to accomplish this, I make the rubber material of the bumper sufficiently soft, as related to the size of the body and the diameter of the diaphragm to cause the bumper to automatically limit the suction stroke to the amount of water available, and I find that in the pump in actual operation a rubber body of a durometer reading of 45 to 50 gives satisfactory results.

When the suction stroke is thus limited, it is apparent that the bolt head 24 temporarily loses contact with the eccentric tire.

It should also be noted that the diameter of the bumper should be sufficiently large, as compared with its length, to prevent buckling of the bumper during the operation of the pump.

The conical form of the bumper further aids in stabilizing the bumper and in preventing sidewise bending of the same under compression.

I claim:

1. A diaphragm assembly for a diaphragm pump, comprising a disc diaphragm made of resilient material, a drive plate mounted on one side of the diaphragm, a washer plate mounted upon the second side of the diaphragm, a bolt extending axially through the plates and the diaphragm and having a head bearing against the drive plate and having a threaded shank projecting beyond the washer plate, a nut threaded on the projecting end of the shank for clamping the plates upon the diaphragm, the shank having an extremity projecting beyond the nut, and a rubber bumper having one end bearing upon the washer plate and having a stepped recess in said end for clamping over said nut and the extremity of the shank.

2. In a diaphragm pump, a housing having a pump

chamber with an intake port and an exhaust port, a diaphragm mounted in the wall of the chamber with freedom of reciprocating movement for alternate drive strokes and suction strokes, an abutment mounted in the chamber in spaced and confronting relation to a central section of the diaphragm and free to allow liquid to pass around the same, means active on the diaphragm for effecting the drive strokes, and a heavy solid rubber bumper interposed between the abutment and the diaphragm and adapted to be compressed by the drive strokes and to effect the suction strokes, the diaphragm having plates on opposite sides thereof, a bolt extending through the plates and the diaphragm, and a nut threaded upon the bolt from the inside of the chamber, and the rubber

bumper having a socket in the lower portion thereof adapted for clamping upon the nut to cause the bumper to become a fixed part of the diaphragm, with the major portion of the bumper projecting above the nut.

3. In a diaphragm pump, a housing having a pump chamber with an intake port and an exhaust port, a diaphragm mounted in the wall of the chamber with freedom of reciprocating movement for alternative drive strokes and suction strokes, an abutment mounted in the chamber in spaced and confronting relation to a central section of the diaphragm and free to allow liquid to pass around the same, means active on the diaphragm for effecting the drive strokes, and a heavy solid rubber bumper interposed between the abutment and the diaphragm and adapted to be compressed by the drive strokes and to effect the suction strokes, the bumper and the diaphragm having cooperative means for clamping the lower end of the bumper upon the diaphragm, and the abutment having an annular flange adapted for receiving the upper end of the bumper therein.

4. A diaphragm assembly for a diaphragm pump, comprising a disc diaphragm made of resilient material, a drive plate mounted on one side of the diaphragm, a washer plate mounted upon the second side of the diaphragm, a bolt extending axially through the plates and the diaphragm and having a head bearing against the drive plate and having a threaded shank projecting beyond the washer plate, a nut threaded on the projecting end of the shank for clamping the plates upon the diaphragm, and a rubber bumper having one end bearing on the washer plate and having a recess in said end for clampingly engaging over the nut.
